Inventor
Henry J. Ferguson

United States Patent Office.

HENRY J. FERGUSON, OF MANCHESTER, NEW JERSEY.

Letters Patent No. 91,532, dated June 22, 1869; antedated June 7, 1869.

IMPROVED COMPOUND RAILROAD-RAIL.

The Schedule referred to in these Letters Patent and making part of the same.

To all whom it may concern:

Be it known that I, HENRY J. FERGUSON, of Manchester, in the county of Ocean, and State of New Jersey, have invented a new and improved Compound Rail; and I do hereby declare that the following is a full, clear, and exact description of the same, reference being had to the accompanying drawings, forming a part of this specification, in which—

Figure 1 represents a transverse section of a compound rail, constructed according to my improvement, and

Figure 2 a similar view of the several parts.

Similar letters of reference indicate corresponding parts in both figures.

This invention consists in the novel construction and arrangement of the several longitudinal sections of which a compound rail is composed, whereby they are rendered mutually supporting and mutually sustaining in all directions, without the employment of bolts passing transversely through them.

In order that others may understand the construction and operation of my invention, I will proceed to describe it with reference to the drawings.

A is the web, composed of two longitudinal sections, a a, fitting together by tongues and grooves t t, so as to secure the same against vertical displacement.

The lower extremity of this double web A is received within a base-plate, B, having longitudinal locking-flanges b projecting upward from its edges, whereby the lateral displacement of the lower portion of the web, and the separation of its sections a a, are prevented.

C is a head or cap, composed preferably of steel, and having longitudinal locking-flanges c c projecting downward from its edges, for clasping the upper extremities of the sections a of the web A, thereby preventing the lateral displacement of the upper portions of the same.

Extending from the central portion of the under side of the head C, and lengthwise thereof, is a continuous longitudinal dovetailed projection or tongue, g, which is received within a dovetailed groove, e, formed in the upper portion of the web A, and between the sections a.

This dovetailed groove e is made sufficiently wider than the corresponding tongue g, so as to permit the said tongue to drop vertically into it, and also to leave a space between the inner surface of the one and outer surface of the other, suitable for containing zinc, or any other easily fusible metal, or other material or compound capable of being applied in a plastic or molten state.

This metal or compound is applied to the said space around the tongue g in a liquid state, by pouring it through openings f, which pass vertically through the head C, and communicate, through the tongue g, with the groove e.

D is a clamp, with its extremities d turned upward

and inward, so that when fitted upon the rail, will clamp, by means of its upwardly and inwardly-bending extremities d, the upper side of the base of the web A, thereby holding it securely to the base-plate B.

Clamps of this kind are applied to the rail at intervals of, say, every two feet.

In laying this compound rail, the base-plates B are first laid, and secured to the cross-ties; the corresponding sections a of the web A are next placed together, and laid upon the base-plates B, between their upturned edges b, and in such manner that the said sections break joints both with each other and with the base-plates B.

The clamps D, which, previous to their adjustment upon the rails, are left with one end straight, to permit them to be slipped under the base of the rail, in a direction transverse thereto, are then applied at suitable intervals, and then bent and tightened around the base-plates B, and upon the lower part of the web A, by means of a hammer, or other suitable implement, so as to securely clamp together the said parts, as is illustrated in fig. 1.

The heads or caps C are next placed upon the upper side of the webs A, in such manner as to break joints with the webs A and base-plates B.

The heads C should be so adjusted upon the webs A that the dovetailed tongue g will rest within the dovetailed groove e, and so as furthermore to clasp, by means of their downward extensions c c, the upper part of the sections a a of the web A, thereby to hold said parts together, and prevent an outward displacement or separation of the same.

The heads C are secured upon the webs A by means of the zinc, or other metal or material, poured through the openings f into the groove e, which fills the space around the tongue g, and thereby connects together the said parts.

Other material or compound, capable of being applied in a plastic or molten state, may be used instead thereof, but it should be preferably a material or compound susceptible of being softened or melted by the application of heat, so that a broken or damaged head may be removed at any time, by first building a fire upon that part of the rail containing the damaged head, and melting or softening the said material or compound.

The flanges b b, on the edges of the base-plate B, may be made to extend sufficiently above the base of the web A, so that when the base of the web is adjusted upon the base-plate B, it may be secured thereon by the bending inwardly of the upper portions of the flanges b b, by means of a sledge, or other suitable means.

In this way, all necessity for clamps D may be dispensed with.

What I claim as my invention, and desire to have secured by Letters Patent, is—

1. The compound rail, consisting of the longitudi-

nally-divided web A, flanged base-plate B, and flanged and dovetailed head C, the whole constructed, arranged, and combined substantially as herein shown and described.

2. The dovetailed tongue *g*, and flanges *c c*, on the under side of the head C, in combination with the channel *e* in the web A, serving to unite the head with the web, by filling the cavity around the tongue *g* with molten metal, substantially as shown and described.

3. Combining the head and web of a railroad-rail, by means of molten metal poured in and around a dovetailed tongue and groove, substantially as described.

HENRY J. FERGUSON.
